US00D744421S

(12) **United States Design Patent**
Yonishi et al.

(10) **Patent No.:** US D744,421 S
(45) **Date of Patent:** ** Dec. 1, 2015

(54) **RECHARGEABLE BATTERY**

(71) Applicant: **Sony Corporation**, Tokyo (JP)
(72) Inventors: **Kiyoshi Yonishi**, Fukushima (JP);
Atsuhiro Kumagai, Kanagawa (JP)
(73) Assignee: **Sony Corporation**, Tokyo (JP)
(**) Term: **14 Years**
(21) Appl. No.: **29/521,683**

(22) Filed: **Mar. 25, 2015**

CLAIM

(57) The ornamental design for a rechargeable battery, as shown and described.

DESCRIPTION

FIG. 1 is a front, top, right perspective view of a first embodiment of a rechargeable battery showing our new design;

FIG. 2 is a front, bottom, left perspective view thereof;

FIG. 3 is a front elevational view thereof; and,

FIG. 4 is a top plan view thereof.

Broken lines illustrate unclaimed portions of the rechargeable battery and form no part of the claimed design. Dot-dash broken lines define the boundaries of, but not included in, the claimed design.
